UNITED STATES PATENT OFFICE.

RALPH W. ALLSUP, OF NEW LONDON, IOWA.

GATE.

SPECIFICATION forming part of Letters Patent No. 772,996, dated October 25, 1904.

Application filed June 28, 1904. Serial No. 214,489. (No model.)

To all whom it may concern:

Be it known that I, RALPH W. ALLSUP, a citizen of the United States, residing at New London, in the county of Henry and State of Iowa, 5 have invented certain new and useful Improvements in Gates, of which the following is a specification.

My invention relates to improvements in gates, more especially the horizontally-swinging type.

It has for its object to simplify construction, cheapen cost of manufacture, provide for readily making the gate, and to promote facility and convenience in the hanging of the 15 same.

It consists of certain structural features, as well as the combination and arrangement of parts, substantially as hereinafter more fully disclosed, and particularly pointed out by the 20 claims.

In the accompanying drawings, illustrating the preferred embodiment of my invention, Figure 1 is an elevation of the latter. Fig. 2 is a cross-section taken on the line $x-x$ 25 of Fig. 1. Fig. 3 is a broken section produced on the line $y-y$ of the same figure. Fig. 4 is a view showing certain disassociated parts or members of one of the hinges of the gate, and Fig. 5 is a view showing the slat 30 rear-end securing members or parts also disassembled.

In the carrying out of my invention I construct the gate generally of longitudinal slats 1, which may be light and spaced short intervals apart and secured in proper relative position by parallel transverse bars 2 and $2^a 2^b$, also by duplicate parallel bars or braces 3 extending from and between diagonally opposite corners of the gate, the bars 2 being 35 secured in duplicate laterally at the forward end and at about the mid-length of said gate, respectively, as presently fully disclosed. Said bars 2, both at the forward end of the gate and at its mid-length, are of right-angled construction in cross-section, the inner arms of each pair of opposed bars are united and bolted to the respective gate-slats by common bolts and nuts 4, while the other or outstanding arms of said bars serve to brace and give 40 rigidity to the inner arms, accordingly brac-

ing the gate generally. The bars $2^a 2^b$ are also united and bolted laterally to the respective gate-slats at the rear end of the gate by common bolts and nuts 5. The bar 2^a has a lateral rear-edge extension or member 2^x , 55 which laps or overlies the corresponding ends of the gate-slats and that edge of the bar 2^b , thus forming a closure therefor. This is, however, an incidental function of said lateral rear-edge extension 2^x , it serving in addition 60 a more important office in connection with the formation of the hinges of the gate, as will be made apparent presently.

Hinge members 6 6^a are applied laterally to the top and bottom gate-slats at the usual 65 points, as the rear corner edges thereof, and each comprises a bent metal strap 6^{aa} , forming a yoke 6^b , with its inner end portions or terminals embracing and suitably bolted to the opposite surfaces of the gate-slat and 70 similarly to the bars $2^a 2^b$. Said yoke extends a suitable distance beyond the rear edge or end of the gate to effect connection with and receive the other or pintle member of the hinge, (not shown,) projecting or secured, as 75 well understood, from the post (not shown) provided for that purpose. It will be noted that the lateral rear-edge extension 2^x of the bar 2^b is thus by the application of the hinge members $6 6^a$ to the bars $2^a 2^b$, as above 80 described, caused to form the inner end walls of the openings of the yokes $6 6^a$. Also arranged within each yoke 6^a are a removable I-shaped filling-in block 7 and a correspondingly-shaped bearing-block 7 a , having a concaved or curved surface presented toward or facing the like surface of said yoke, said bearing-block and the latter thus forming an eye for the reception of the pintle member of the hinge, as above noted. By having the filling-in blocks and the bearing-blocks I shape, flanges are furnished thereon at their upper and lower ends, as at 7^b , projecting beyond the upper and lower edges of the yoke 6^b to effect the holding of said blocks in proper 95 position in the latter without the use of separate securing means, as would otherwise be required. The filling-in blocks may be wedged outward and in the direction of the bearing-blocks or others of greater cross-section sub- 100

stituted therefor as the latter wear away in use for compensating such wear, and the hinges thus be constantly kept in repair in this respect, as will be readily appreciated.

5 The oblique braces 3 are suitably bolted up with the end bars 2 and 2^a 2^b, also with the upper hinge member 6^a to the bottom and top gate-slats, as they may be also to the intermediate gate-slats.

10 Latitude is allowed as to details herein, as they may be changed as circumstances suggest without departing from the spirit of my invention and the latter still be protected.

I claim—

15 1. A gate having rear-end transverse bars, one having a rear-edge lateral extension lapping that end of said gate and hinge members having the inner end walls of their pintle-receiving sockets or openings formed by said 20 lateral extension, and bearing and filling-in

blocks arranged in said hinge members inward of the position occupied by the pintle members.

2. A gate having rear-end transverse bars, one having a rear-edge lateral extension, and 25 hinge members, the inner end walls of their pintle-receiving openings formed by said lateral extension and bearing and filling - in blocks arranged in said hinge member, inward of the position occupied by the pintle member, 30 said blocks having lateral flanges at their upper and lower ends, projecting beyond said hinge members.

In testimony whereof I have signed my name to this specification in presence of two witnesses.

RALPH W. ALLSUP.
